Primary Examiner — Jonathan J Han(74) *Attorney, Agent, or Firm* — Greer, Burns & Crain, Ltd(57) **CLAIM**

The ornamental design for a footwear upper and midsole as shown and described.

DESCRIPTION

FIG. 1 is a front perspective view of a footwear upper and midsole showing my new design;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The broken lines in FIGS. 1-7 represent portions of the footwear that form no part of the claimed design. The broken lines at the interior of the footwear which define the bounds of the claimed design form no part thereof.

1 Claim, 7 Drawing Sheets(56)
